UNITED STATES PATENT OFFICE

2,107,596

PRESSURE COMPENSATING DEVICE FOR
MULTIPLE GAS CHAMBERSPierre Marcel Bourdon, Paris, France, assignor
to Michelin et Cie., Clermont-Ferrand, France,
a corporation of FranceOriginal application April 19, 1935, Serial No.
17,365. Divided and this application September
30, 1936, Serial No. 103,462. In France
June 12, 1934

5 Claims. (Cl. 152—12)

The present invention relates to improvements in pressure compensating devices for multiple gas chambers and is a division of application Serial No. 17,365, filed April 19, 1935, and in one instance the invention relates more particularly to a device for equalizing pressure between the air chambers of twin automobile tires.

Another object of the invention is to produce an improved compensating device which may maintain a constant pressure difference between two gas or air chambers where it is desirable that the pressure be not equalized but be maintained at predetermined pressure differences.

The invention has for a further object the production of a compensating device for the purpose indicated which is made up of simple parts grouped in a simple organization. The device forms a unit which may be used either alone or in any appropriate numbers or combinations.

With the foregoing and other objects in view, the invention will be described more particularly in the following specification and more particularly pointed out in the appended claims.

In the drawings, in which like parts are denoted by the same reference characters throughout the several views,

Figure 1 is a diagrammatic view of a unitary compensating device constructed in accordance with the present invention.

Figure 2 is a section taken on the line 2—2 in Figure 1.

Figure 3 is a view similar to Figure 2 with the membrane sleeve inflated.

Figure 4 is a diagrammatic view showing a modified form of the device.

Figure 5 is a cross section taken through a commercial device showing the unitary construction of Figure 1.

Figure 6 is a similar view showing a commercial application of the modified device according to Figure 4.

Figure 7 is a cross section showing a combination unit.

Figure 8 is a diagrammatic view showing a grouping of a plurality of the units, and

Figure 9 is a sectional view showing a commercial adaptation of the grouping of the plurality of the units.

Referring more particularly to the drawings, and for the present to Figures 1, 2 and 3, wherein there is shown a simple form of unit designated generally at A, it designates a tube having chambers 2 and 3 separated by a partition 4. The chamber 2 may connect with the interior air space of one automobile tire or with any other

gas container, while the tube end 3 may connect with the air space of a twin or other automobile tire or other gas container. The chambers 2 and 3 are provided with one or more ports 5 and 6 disposed on opposite sides of the partition 4 and these ports are arranged to communicate with the interior space housed about by a flexible or elastic membrane sleeve 10 bound securely, as indicated at 7 and 8, to the metal or other tube 1 at opposite sides of the ports 5 and 6.

The device may be contained within a collar or casing 9 allowing ample room for the membrane 10 to expand outwardly from the outer wall of the tube 1. The membrane 10, by reason of its own inherent elasticity, will seek a position stretched rather tightly over the outer cylindrical circumference of the tube 1 so as to close both ports 5 and 6 and in this respect it functions as a valve for both of the ports, acting independently and locally upon each port.

When there is no pressure in the chambers 2 and 3, the membrane sleeve 10 is applied closely or tightly about the tube 1 thus closing the ports 5 and 6. This is illustrated in Figure 2 by "position I."

Whenever the chamber 2 contains pressure in excess of the contractile strength of the membrane sleeve 10 it will act through the port 5 upon such membrane thus inflating the membrane 10 by first causing it to bulge locally away from the tube 1. As soon as the membrane is lifted off the port, as shown in position II in Figure 2, the effective area of the membrane increases and it is inflated to the position III of Figure 3, where in the ports 5 and 6 are in communication. In this position communication between the chambers 2 and 3 is established and gas flows freely

from chamber 2 into chamber 3 until pressures in the two chambers become equal. After the pressures have been thus equalized if the pressure in one chamber, at any time, for any reason becomes greater than that in the companion chamber, the gas flows from that chamber to the other chamber through the equalizing device until stability of pressures is restored. This will go on automatically maintaining a condition of

equality of pressures of the two chambers 2 and 3. On the other hand, should the pressure fall below the predetermined maximum in any chamber, then the pressure from the companion chamber will flow over to distribute the loss and maintain pressure equality. This is true within limits. Of course should a blow-out occur in one of the tires thus completely evacuating, for instance, the chamber 3, then if the compensating valve 55

device remained open, the companion tire or chamber 2 would also be evacuated completely through the rupture of the blown-out tire and the vehicle would lose the complete support of both of the twin tires.

In emergencies such as this the elastic membrane sleeve 10 will collapse against the outer wall of the tube 1 after the pressure in the chamber 2 has fallen below the limit required to expand this membrane against its inherent elasticity. Such limit will be chosen to be one such as will retain sufficient pressure in the remaining tire to properly support the vehicle without endangering the tire itself, thus enabling the vehicle to be run on this remaining tire for a considerable distance if need be before reaching a garage or service station where repair or replacement may be made to the blown-out companion tire. In closing, the membrane sleeve 10 will first collapse against the port 6 of the chamber 3 in which the heavy fall in pressure has occurred by reason of the blowout. In other words the device will pass through the position shown in Figure 2 before it returns to the "position I." The distention of the membrane sleeve 10 in response to the pressure within either chamber will depend upon the tension inherent in the rubber sleeve 10 and also upon the port area or diameter of the ports 5 and 6. From the moment the membrane sleeve 10 closes to the position shown in Figure 2, communication is prevented between the two chambers 2 and 3 and the deflating chamber can continue to deflate without affecting the pressure condition of its companion chamber.

In practice the following effects will be secured from the use of the improved compensating device.

1. When inflating, the two chambers or tires will be caused to receive equal pressures.

2. The two chambers will remain at equal pressures provided such pressures exceed a predetermined minimum which minimum depends upon the tension of the rubber sleeve 10 and the cross sections or port areas of the ports 5 and 6.

3. If the pressure in one of the chambers falls below this predetermined pressure minimum the pressure in the companion chamber ceases to drop.

The collar or device 8 is located a desired distance from the tube 1 so as to allow for the free expansion and contraction of the membrane sleeve 10 but such collar 8 acts as a stop to arrest any undue inflation of the membrane 10. It also reinforces and supports the membrane 10 in case of excessive inflation to avoid injury or bursting of the membrane sleeve. The interior space between the collar 8 and the membrane sleeve 10 may be open at the ends of the collar to the atmosphere so that there is no confined air space interfering with the free movement of the membrane sleeve 10.

Referring more particularly to Figure 4 in which a modified form of device indicated generally at B is provided, a similar arrangement of tube 1, chambers 2 and 3, partition 4, ports 5 and 6 and membrane sleeve 10 is provided; but in this case instead of providing a collar, an enclosed casing 9^a is fitted tightly to the tube 1 at the opposite ends of the membrane sleeve 10 and this casing 9^a houses a confined volume of air about the membrane sleeve 10.

The end walls 9^c of the casing 9^a are provided with out-turned flanges or bearing portions 9^b

which are fitted in an air-tight manner about the pipe or tube 1. The confined space within the casing 9^a is placed in communication with one of the chambers, for instance the chamber 3, by an orifice or port 12. By reason of this arrangement it will be seen that the chamber 3 will always be at a lower pressure than chamber 2. Assume that pressure is being introduced into chamber 2; then acting through the port 5 and against the rubber membrane sleeve 10 it will expand such sleeve away from the tube 1 in the manner already described in connection with Figures 1, 2, and 3, and shown in Figure 4 so that ultimately the port 6 will be opened and communication thus established between chambers 2 and 3 with a consequent interchange of pressure between these two chambers. During this interchange of pressure the fluid which is admitted to chamber 3 will pass through the orifice 12 and into the confined space of the enclosed casing 9^a about the exterior surface of the rubber membrane sleeve 10. Thus the sleeve 10 will be subject to the pressure of chamber 2 from within and of the pressure of chamber 3 from without. The sleeve 10, as previously explained, is of rubber stretched over the tube 1 so that it inherently seeks a position fitting tightly against the tube 1 and its ports 5 and 6.

This elastic tension or contractile stress within the rubber sleeve 10 is augmented or supplemented by the external pressure in the enclosed casing 9^a acting on the outside of the sleeve. Thus the pressure within the chamber 2 must overcome this combined inherent stress and external pressure and as long as it can do so the ports 5 and 6 will remain open and there will be a flow of gas from the chamber 2 to the chamber 3. It will be seen however that the membrane sleeve 10 will contract and close the ports 5 and 6 before any equality of pressure is established in chamber 3 and therefore chamber 3, in the arrangement shown in Figure 4, can never reach the same pressure as in chamber 2. The pressure differential would depend upon the elastic strength or stress of the membrane sleeve 10 and this may be selected so as to give the desired result. Considered in another way the pressure in chamber 3 will always be less than that in chamber 2 by the amount necessary to open the membrane sleeve 10. When pressure is cut off from being introduced into the chamber 2, counter-pressure within the enclosed casing 9^a will promptly cause the membrane sleeve 10 to close against the ports.

If at any time after inflation there should occur a pressure drop in chamber 3, or a rise in chamber 2, so as to disturb the pressure difference, the membrane 10 will again open to permit flow from 2 to 3 to compensate for the variation.

This flow will continue until the inherent tension of the rubber in the sleeve 10 will cause this sleeve to close against the port 6. Further flow of the fluid will then of course be prevented. If pressure falls in the chamber 2 or rises in the chamber 3, obviously the membrane sleeve 10 will remain closed against the ports 5 and 6 and no movement of the gas from the chamber 3 to chamber 2 will be permitted.

In short, the device B shown in Figure 4 will have as its effect to maintain between chambers 2 and 3 a normal difference of pressure which will depend, all other things being equal, on the initial or inherent tension of the sleeve 10. If the pressure becomes lower in the low pressure chamber

the pressure in the high pressure chamber will drop by reason of the opening of the valve and the flow of gas from chamber 2 to chamber 3; and this action will continue until sufficient pressure in chamber 3 is established to permit closing of the valve 10, at which time there will be a substantial re-establishment of the pressure differential between the two chambers 2 and 3. Thus the pressure differential will be for all purposes a constant. Whenever there is a rise in pressure in the low pressure chamber 3, or a drop in pressure in the high pressure chamber 2, then the device acts as a check valve preventing flow from chamber 3 back to chamber 2.

Referring more particularly to Figure 5, 2^a and 3^a represent two tubes communicating at their outer ends separately with two chambers or tires or the like. At their inner ends the tubes connect with ducts or channels 14^a and 14^b which are separated by the partition 4^a. The channel 14^a communicates at 19 with a passage 18 in the valve stem or inflating nozzle 20. The channels 14^a and 14^b are made in a body 30 of metal or other suitable construction in which is also constructed the partition 4^a. The channels 14^a and 14^b on opposite sides of the partition 4^a respectively lead beneath a rubber membrane sleeve 10^a which normally shrinks or contracts against the ports 5^a and 6^a in the outer ends of the channels. The sleeve 10^a may be held in place by a ring 15 and a nut 16 and the valve stem 20 may be also held in place by an appropriate washer and nut 31 screwed on to the same and bearing against an enclosing cap 17. However the enclosing cap 17 will merely form a protection for the rubber sleeve 10^a but will not exclude atmospheric air from the outside of said sleeve. Thus the device is a commercial adaptation of the form A shown in Figures 1, 2, and 3. A pump or inflating hose is connected with the valve stem 20 and air or other fluid is pumped through the passages 18 and 14^a into the tube and its chamber 2^a.

When the pressure rises to such an extent as to exceed the initial or inherent strength or tension of the membrane sleeve 10^a, this sleeve will be expanded away from the ports 5^a and 6^a and the pressure will flow from one channel 14^a into the other channel 14^b and thus into the tube 3^a and its chamber. Therefore according to this device there will be an equalization of pressures maintained at all times between the two chambers, at least as long as the pressure is high enough to keep the membrane sleeve 10^a open. In other words the equality of pressure is maintained so long as conditions are normal. If an excessive deflation occurs in one of the chambers, the deflation in the other chamber is limited by the initial or inherent tension of the sleeve 10^a which may be chosen as strong as one wishes. The elastic strength or tension of the rubber out of which the sleeve 10^a is made may be very strong or comparatively weak. Where it is of great strength, high pressures will be required to raise the same from the ports 5^a and 6^a. Therefore where a high strength rubber sleeve 10^a is employed and a severe drop in pressure is caused in one of the chambers, the other chamber will only give up a small portion of its pressure to that of the deficient chamber owing to the fact that after a comparatively small drop in pressure from the high pressure chamber, the strong membrane sleeve 10^a will close thus preventing the loss of any further pressure in such high pressure chamber.

On the contrary if it is desired that equality of

pressure in the chambers be maintained without regard to a rapid and low drop in the pressure in one of the chambers then the material of which the membrane sleeve 10^a is made may be so selected as to be of very small strength or tension in which case it will require very little pressure to lift it off its seat and away from the ports 5^a and 6^a and thus an interchange of pressure will go on for a long time and to a comparatively low degree.

Referring more particularly to Figure 6, this figure shows a commercial adaptation of the device B which is illustrated diagrammatically in Figure 4. In this Figure 6 the low pressure chamber is indicated at 3^b while the high pressure chamber, or the tube connecting the high pressure chamber with the device, is designated at 2^b. These tubes connect with the casing 30^b and with chambers to opposite sides of the partition 4^b. The hollow valve stem is represented at 20^b and 20 serves to introduce air into the chamber 2^b. The ports 5^b and 6^b are controlled in the manner already described by a rubber or elastic sleeve 10^b which is contained within a casing 17^b surrounding the membrane 10^b and having a tight fit at 23 25 with the casing 30^b. The casing has an orifice or port 12^b establishing communication between the low pressure chamber 3^b and the chamber confined by the casing 17^b.

This casing 17^b makes an air-tight fit with the 30 casing at 23 and also at 31^b.

A device according to this construction has the following advantages:

(a) The two chambers 2^b and 3^b are inflated to unequal pressures depending on the tension of the 35 membrane 10^b.

(b) If the pressure drops in the low pressure chamber 3^b it drops also in the high pressure chamber 2^b until the pressure in the high pressure chamber 2^b falls so low as not to be able to lift 40 the valve sleeve 10^b against its tendency to collapse against the ports 5^b and 6^b.

(c) If the pressure rises in the high pressure chamber 2^b it rises also in the low pressure chamber 3^b.

(d) If the pressure drops in the high pressure chamber 2^b or rises in the low pressure chamber 3^b there will be no effect on the other chamber.

Referring more particularly to Figure 7, in this figure there are two of the devices B coupled together. The valve stem or hollow nozzle is indicated at 20^c and serves to introduce gas under pressure into the two chambers 2^c and 2^d.

The chamber 2^c of one of the units B is divided by a partition 4^c from the low pressure chamber 3^c, which low pressure chamber communicates by means of a port or annular channel 12^c with the confined space on the exterior of the elastic membrane sleeve 10^c.

An air-tight casing 17^c serves to confine the gas 60 about the membrane sleeve and this membrane sleeve is adapted to normally collapse and close against the ports 5^c and 6^c.

The high pressure chamber 2^d of the companion unit B communicates with a port 5^d beneath the elastic membrane sleeve 10^d. The low pressure chamber 3^d is separated by the partition 4^d from the high pressure chamber 2^d and a port 6^d, normally closed by the sleeve 10^d enables communication to be made between the two chambers. A port 12^d leads the pressure to the exterior of the membrane sleeve 10^d, the space about this membrane sleeve being confined by the air-tight casing 17^d. The two casings 17^c and 17^d may be removably mounted, as by screw thread- 75

ing, upon a central block 40 and the two units B are thus combined into a single commercial device.

If the two membrane sleeves 10^c and 10^d are identical in point of strength and tension, then the pressures in the two low pressure chambers 3^c and 3^d will be the same. If the strengths or tensions of the sleeves are different, then the pressures in the low pressure chambers will be proportionately different. As soon as the source of compressed gas is cut off at the nozzle 20^c then the rubber sleeves 10^c and 10^d will close preventing any further transfer of pressure from the central chambers 2^c and 2^d to the outer low pressure chambers 3^c and 3^d.

As a result after inflation the two low pressure chambers 3^c and 3^d are independent of one another.

Referring more particularly to Figure 8 there is shown a combined arrangement showing four of the units A', A², B', B². These units are mounted in series between chambers 41 and 42. These chambers are connected by two pipes or tubes 43 and 44. In the tube 43 are disposed the unit A' and the unit B'. In the other pipe there are included the unit A² and the unit B². The unit B' permits the passage of gas from the chamber 42 to the chamber 41 through the tube 43, that is if the pressure in the chamber 41 is at any time lower than that in the chamber 42. The unit B² permits the passage of fluid from the chamber 41 to the chamber 42 where the pressure in the chamber 42 is lower than that in 41. The inflating nozzle 20^c is connected with the tube 44 between the chamber 41 and the unit A². This arrangement functions as follows:

When fluid under pressure is introduced at 20^c it will fill the chamber 41 but be arrested by the unit B' from flowing further along in the tube 40 or pipe 43 because this pressure has access to the outside of the membrane sleeve in the device B'. Therefore the pressure will aid the inherent elasticity of the membrane sleeve to remain closed.

Consequently the pressure will back up in the chamber 41 and extend along the pipe 44, passing freely through the unit A² and also freely through the unit B² as the pressure on this side communicates only with the interior of the membrane sleeve and not with the exterior thereof until the pressure flows around to the opposite side of the partition whereupon it enters the low pressure chamber 42, and such pressure gets to the outside of the membrane sleeve in the unit B² and assists the inherent elasticity of that sleeve to close the sleeve against the ports. Therefore the chamber 42 will be the low pressure chamber. Pressure of course from this chamber 42 will run to the left along the pipe 43 passing freely through the unit A' but being arrested at the unit B' because this pressure must lift the membrane sleeve and it cannot do so against the inherent tension of the sleeve and the greater pressure existing upon the outside of that sleeve. In other words the pressure upon the inside of the membrane sleeve in the unit B' has been reduced over that received through the nozzle 20^c by virtue of the unit B' but there has been no diminution of this pressure through the chamber 41 and upon the outside of the membrane sleeve in the unit B'. The difference in pressure between 41 and 42 will thus be governed by the strength of the membrane sleeve in the unit B².

Flow in the pipe 43 is only permitted in the direction indicated by the arrow as the unit B'

will prevent flow in the opposite direction as already explained.

In the companion pipe 44 flow will only be permitted in the opposite direction as indicated by the arrow, the unit B² preventing flow in the opposite direction.

The high pressure chamber is indicated at 41 and the low pressure chamber at 42 and the pressure differential between these chambers will depend upon the strength or the elastic tension of the membrane sleeve in the unit B². The pressure in 41 must always be strong enough to open this membrane sleeve in the unit B². If the pressure drops in chamber 42, fluid flows through the pipe 44 and the pressure drops in chamber 41. Such pressure in 41 will drop until the pressure in this side of the device no longer exceeds the pressure in the side 42 plus the strength of the membrane sleeve in the unit B². If the unit B² is used alone then the strength of the membrane sleeve in this unit will wholly determine the pressure differential between the two chambers but by reason of the use of the unit A² the limit in the drop of pressure in the chamber 41 can be governed so that preferably the pressure will not drop quite as much as it would if the unit B² were used alone.

If pressure in the chamber 41 tends to rise, the units A² and B² permit the flow of pressure towards the chamber 42 so that the difference between the pressures in the chambers 41 and 42 remains always equal to a constant which varies according to the strengths of the membrane sleeves in the two units. If the pressure in chamber 42 tends to rise while still remaining lower than the pressure in chamber 41, no action will take place in the device as the lower pressure on the side 42 cannot pass through the unit B' owing to the superior pressure on the side 41. Of course the unit B² will not permit passage back from chamber 42 to the chamber 41. The same thing happens if a small drop occurs in pressure in the side 41 but which drop is not sufficient to carry the pressure lower than in the side 42. When the pressure in 41 falls sufficiently below that in the side 42, or when the pressure in the side 42 rises sufficiently above that in the side 41 to exceed the strength or tension of the membrane sleeve in the unit B' plus the incumbent weight of the pressure upon this membrane sleeve from the side 41, then a compensating flow of pressure occurs from the side 42 over to the side 41. If the pressures fall below the strength or tension of the membrane sleeve in the unit A' this unit will close and prevent any flow from 42 to 41. Referring more particularly to Figure 9, the units A', A², B', and B² are arranged in the form of a cross with the opposite chambers indicated at 41^a and 42^a. The valve stem or filling nozzle is indicated at 20^a and communicates directly with the chamber 41^a and also with the unit A², as indicated by the arrows. After passing through the unit A² the flow is around to the unit B² and by reason of the wall 45 the gas is required to pass through the unit B² before getting into the chamber 42^a. This chamber 42^a communicates with the unit A' and through this unit A' with the unit B' in the opposite horizontal branch of the cross, there being also an imperforate wall 46 in this branch of the cross to require the gas to flow through the unit B' and raise its diaphragm before getting into the chamber 41^a. The horizontal and vertical intersecting partitions 47 and 48 are also in the form of a cross, dividing the chambers

or passages and forming in effect the pipes or tubes 43 and 44 of Figure 8 requiring that the gases raise the membrane sleeves of the various units before getting to the opposite sides of the partitions.

It will be obvious that various changes may be made in the construction, combination and arrangement of parts which could be used without departing from the spirit of my invention and 10 I do not mean to limit the invention to such details except as particularly pointed out in the claims.

Having thus described my invention, what I claim and desire to secure by Letters Patent of 15 the United States is:

1. A device of the character described, comprising adjacent non-communicating tubular gas chambers having ports therein opening outwardly, and an elastic sleeve encompassing said ports 20 and having an interior space when inflated for establishing communication between the ports, means for securing the ends of the sleeve in an air tight manner to said chambers, said sleeve normally stretched tightly over said ports and 25 closing the same, and an enclosed gas tight member extending about said sleeve and in communication with one of the chambers.

2. In a device of the character described, a tube with a partition dividing the same into opposite chambers, said tube having ports on opposite sides of said partition communicating internally with the two chambers and opening outwardly, and an elastic sleeve having its ends bound tightly to the tube at opposite sides of 30 said ports and being initially stretched over and closing said ports, but subject to inflation by pressure within the chambers acting through the ports to move away from the tube and from the ports, a casing having imperforate side and end 35 walls fitted closely to said tube about the sleeve and forming an interior pressure space, said tube having a port establishing communication between said pressure space and one of the chambers.

3. A pressure compensating device for use between two containers of gas under pressure comprising, two adjacent gas containing members one for communicating with each of the two containers and each of said members having a 5 port opening therefrom, an elastic membrane stretched across both of said ports normally to close the same and prevent communication therebetween and secured to the members in an air tight manner, said membrane adapted to be 10 opened by pressure exerted at said ports to permit communication between the members, and means for transmitting the pressure gas in one of said members to the outside of the membrane tending to maintain the membrane closed and 15 preventing completely passage of gas from the one of said members.

4. In a device of the character described, adjacent gas chambers for communicating with gas containers, each of said chambers having a 20 port opening therefrom, an elastic membrane secured in an airtight manner over said ports, and a gas tight cover over said membrane, one of said gas chambers having an opening therein communicating with the interior of said cover to 25 transmit the pressure gas of said container to the outside of the membrane.

5. A connector for two gas holding vessels comprising adjoining tubes one for communicating with each of said vessels and each having 30 adjoining ports opening outwardly, an elastic sleeve covering both of said ports and secured to the tubes in an air tight manner and adapted to be raised by pressure of gas operating through said ports to connect said ports together, and means for directing the pressure of 35 gas in one of said tubes on the exterior of said sleeve to resist raising by pressure in the other of said tubes and to prevent raising by pressure in the adjoining tube.

40

PIERRE MARCEL BOURDON.
